UNITED STATES PATENT OFFICE.

SAMUEL S. FRETZ, SR., OF PHILADELPHIA, PENNSYLVANIA.

SELF-OPENING UMBRELLA.

Application filed September 12, 1921. Serial No. 500,238.

To all whom it may concern:

Be it known that I, SAMUEL S. FRETZ, Sr., a citizen of the United States, residing in the city and county of Philadelphia, State 5 of Pennsylvania, have invented a new and useful Self-Opening Umbrella, of which the following is a specification.

My invention consists of a self-opening umbrella or parasol provided with a cup in 10 which the tips of the ribs may be contained, means for locking the runner, and means for releasing the tip cup and the runner, as will be hereinafter further described.

The invention is satisfactorily illustrated 15 in the accompanying drawing, but the important instrumentalities thereof may be varied, and so it is to be understood that the invention is not limited to the specific details shown and described, but I reserve the 20 right to such modifications as come within the scope of the claim.

Figure 1 represents a side elevation of an 25 umbrella in closed condition embodying my invention.

Figure 2 represents a side elevation of the 30 frame of the umbrella in open condition.

Figures 3, 4, and 5 represent partial longitudinal sections, and partial side elevations of portions of the umbrella on enlarged scales, certain members being in different positions in the three figures.

Figure 6 represents a transverse section 35 on line 6-6 Figure 4.

Figure 7 represents a side elevation of a 40 detached portion.

Figure 8 represents a transverse section 45 on line 8-8 Figure 4.

Figure 9 represents a side elevation of a 50 portion of Figure 8 in a different position.

Similar numerals of reference indicate 55 corresponding parts in the figures. Referring to the drawings.

1 designates the ribs, 2 the stretchers, 3 the runner and 4 the stick of an umbrella. 45 On the lower portion of the runner is the disc or head 5 and the collar 6, said disc being stationarily connected with the runner, and said collar being movable over said disc and the adjacent portion of the runner.

50 A portion of the collar surrounds the disc and is of considerably greater diameter than the latter forming the cup 7 which is adapted when the umbrella is closed to receive the tips of the ribs and retain them 55 therein, avoiding spreading apart of the ribs, a feature of itself known in the art.

The inner end of the collar 6 is connected with the reduced cylindrical portion 8 which is slidable with the collar on the contiguous part of the runner 3, said portion having 60 surrounding it opposite to said collar 6 the auxiliary tapered collar 9 which is connected with the runner and movable therewith. Its lower outer end is inturned forming the flange 10 which end is towards the stick of 65 the umbrella.

In the head of the collar 9 is the slot 9^x and on the adjacent end of the cylindrical part 8 of the tip cup is the tongue 8^x which is adapted to enter freely said slot so as to 70 guide the tip cup in its motions and prevent rotation of the same.

Near the handle of the umbrella is the resilient catch 11 which is formed of a movable bar having in its side a plurality of 75 shoulders such as 12 and 13 which are adjacent to each other, and the exterior operating finger piece 14, the catch being guided in a slot in the stick as well known.

Interposed between the disc 5 and the 80 cylinder 8 is the spring 15 whose tendency is to move the tip cup 7 from the disc 5, so as to release the tips of the ribs, see Figure 4, as will be hereinafter more fully described.

Attention is drawn to the fact that the 85 shoulders 12 and 13 are of different lengths, the shoulder 12 being the shorter, and that in closing the umbrella the collar 6 is drawn down with the runner. Then the ribs are folded inwardly and the tips thereof placed over the disc 5, when the collar 6 is moved by hand away from the handle and then let go when its cup surrounds the tips and prevents the ribs from opening out, see Figure 95 3. At the same time, the spring 15 is compressed and the tongue 8^x is rested against the shoulder 12 as a stop against a return movement of the collar 6. The flange 10 engages with the shoulder 13 and so locks 100 the collar 9 and consequently the runner, whereby the opening of the umbrella is prevented.

Attention is also directed to the fact that the runner will be engaged by a suitable 105 spring which may be contained in the stick which is made hollow for the purpose, or springs may be connected with the stretchers and ribs, in either case to cause the self opening of the umbrella, a feature of itself 110 known in the art.

When the umbrella is to be opened, the

catch 11 is pushed in a sufficient distance, then the shoulder 12 slides inwardly on the end of the tongue 8^x and clears said end when the tip cup is released. Then the 5 spring 15 is permitted to expand whereby it moves the tip cup from the disc 5 and consequently from the tips, see Figure 4, when said tips are released of the cup and the ribs may spring out to a limited extent preparatory to the opening of the umbrella. 10 Then the catch is pushed in to full extent when the shoulder 13 clears the flange 10 of the auxiliary collar, thus releasing the latter and consequently the runner, when 15 the spring employed to open the umbrella exerts its power on the runner and draws on the latter so as to cause it to slide on the stick to open the stretchers and consequently the ribs, thus causing the self opening of 20 the umbrella.

In closing the umbrella the runner is drawn down by the collar, and the ribs are gathered in so that the tips are disposed towards the runner when the tip cup 6 is 25 moved up so that the cup encircles the tips and controls them and consequently the ribs from outward motions. Then the end of the tongue 8^x is seated on the shoulder 12 of the catch 11, which latter has moved out by 30 its resiliency, and the spring 15 is com-

pressed. Simultaneous therewith the flange 10 engages with the shoulder 13 of the catch and so locks the collar and consequently the runner, thus retaining the umbrella in closed condition and controlling the self opening spring from action, but when it is desired to again open the umbrella the catch is operated to release the tip cup and the runner in the manner set forth. 35

Having thus described my invention what I claim as new and desire to secure by Letters Patent, is:—

In a self opening umbrella having a runner, a tip cup slidable thereon, means for releasing said tip cup, a tapered collar on the runner, a catch on the stick of the umbrella, said catch being provided with means for retaining said tip cup in operative position, and with means for engaging said collar for preventing the opening movement of the umbrella, said tip cup having thereon a tongue, and said collar having in its head a slot in which latter said tongue is slidable as a guide for the tip cup in its motions, and serving to prevent rotation of the tip cup. 50 55
